UNITED STATES PATENT OFFICE.

GEORGE W. D'ARCY, OF BOSTON, MASSACHUSETTS.

VAPORIZING APPARATUS.

Application filed March 31, 1923. Serial No. 629,208.

This invention relates to vaporizing and humidifying apparatus and especially to that type of such apparatus that is particularly adapted for use in mills, mines and other places where it is desirable to obtain more or less complete vaporization of the water with normally no precipitation.

In the drawings of one embodiment of my invention illustrated and described herein, Fig. 1 is a side elevation thereof; and

Fig. 2, a vertical section of the same.

My novel humidifying apparatus comprises, Figs. 1, 2, a valve body or casing 1, with a threaded cover 2, having in turn a low threaded neck 3, which receives a cap 4 having adjustable connection therewith. The cap 4 is apertured to receive the spindle 5 of a valve head 6, a spring 7 being coiled about the spindle 5, one end seated against the cap 4 while the opposite end is seated against the valve head 6, thus permitting adjustment of the tension against the head and consequent complete control of its movement. This construction forms a controller for the admission and mixture of the liquid and discharge of the vapor having, among others, the advantages hereinafter pointed out.

The head 6 carries a stem supporting member as a diaphragm 8 of thin copper or any suitable material which is firmly held between the opposed edges of the base 1 and top 2.

Extended both outwardly and inwardly from one side of the valve body 1 is a neck 9, the outer end being threaded to receive the pipe connection to be referred to. The neck contains a passage 10, the inner contracted end and outlet of which terminates beneath the inner spindle end 11 and which seats thereover.

The neck 9 is adapted to be connected to any convenient source of water or other liquid supply and herein by means of an elbow 12, nipple 13 and union 14, the passage 15 through which is considerably contracted. A fine sieve 16 is secured across the interior of the union between its opposed edges.

The bottom of the body 1 is tapped to receive a bushing 17 with a generous passage therethrough, which bushing in turn is interiorly threaded to receive a vapor gauge and vaporizing member in the form of a nipple 18 with a restricted passage 19 of suitable size. Obviously different nipples with

passages of different sizes may be substituted at any time for special occasions or conditions, the size of the passage determining substantially the amount of water to be vaporized.

To the nipple 17 is secured the vaporizing head 20 of preferred construction, that shown herein comprising a long body with a lip 21 on its outer face, discharge apertures 22 thereabove, and a cap 23 on its lower end permitting access to the head if desired for any purpose.

The body 1 is also apertured, Fig. 1, on its side wall and threaded at 24 to receive suitable connection with a source of fluid pressure, such as air or steam, not shown.

The operation of my novel vaporizer is as follows: The air pressure at the supply inlet may be thirteen pounds or greater, but it is usually desirable to keep it as low as possible for economy and from thirteen to fifteen pounds are effective for good results. The water or other liquid pressure at the supply inlet may be anything greater than fourteen or fifteen pounds, it being of little importance so long as the pressure is a little greater than the air pressure.

The valve 11 is closed and the spring 7 adjusted as to tension so that it will maintain the valve 11 closed against the normal pressure of the water whatever that may be, but not against any substantial increase of the water or combined water and air pressure. It is entirely possible to adjust the spring so accurately that almost any increase above the normal in the water or water and air pressure will open the valve. To operate the humidifier, air pressure of approximately thirteen pounds is then admitted to the pipe 24 and when this air reaches the interior of valve chamber 1, it, with the water pressure of fifteen pounds on the lower end of the spindle 5, acts to raise the same and open the orifice to the passage 10 permitting water to flow therethrough and the mixed air and water after being substantially vaporized in the interior of the body 1 which is really a vaporizing member will escape from the apertures 22 in the head in the form of a mist.

Vaporization will continue until the air pressure is shut off when vaporization will stop instantly. Indeed it seems to make no difference whether the water pressure be slightly higher than the air pressure or many

pounds higher, on shutting off the air the valve 6 will be closed by the spring 7.

The nipple 18 in addition to affording regulation of the amount of vapor, and incidentally of water passing to the head 20 acts to further effect vaporization and mixing of the water and fluid as they are crowded through its restricted passage and it may readily be withdrawn to permit access to the interior of the valve 1 for any purpose without removing the head 20.

This construction is very compact, simple and efficient, will operate with low air pressure, thus being economical, and produces extremely light vapor.

This form of controller, requiring less piping than that, for instance shown in application Serial No. 346,425, is particularly advantageous in cases where the space is limited, and where the vaporizing head may be directly connected to the control, or connecting element for the air and fluid pipes and also where it is desired to have the installation as inconspicuous as possible, as for instance without the detachable mixing chamber 15 in my application above referred to.

It is also advantageous, where it is necessary or desirable to operate it at a relatively low air pressure and relatively higher water pressure for the reason that it is expensive to maintain high air pressure while it is usually practicable to obtain water at any reasonable pressure. This form of vaporizer will operate at less air pressure because the air is not obliged to perform the carrying function that it performs to some extent where the other form of construction above referred to is used. In such case the vapor is carried through various lengths of pipe to the several heads, while in the present case the vapor is discharged directly from the valve chamber which becomes the mixing chamber, to the head, without the necessity for traveling through any intermediate length of pipe.

This invention is not limited to the particular embodiment thereof described and illustrated herein, but is more particularly pointed out in the following claims.

I claim—

1. Vaporizing apparatus comprising a controller having a mixing chamber therein, a water inlet, a valve therefor, an air inlet, a compression member for the water valve, and a vapor gauge for and leading from the mixing chamber of the controller; and a vaporizing head connected thereto. 50

2. A vaporizer comprising a controller having an air inlet, a water inlet removed from the outer wall of the controller, a valve for said water inlet, compression means for closing the valve against normal water pressure, and a vapor gauge on and carried by the controller and communicating with the mixing chamber; and a vaporizing head connected thereto. 60

3. A vaporizing controller having a mixing and vaporizing chamber, and an aeriform inlet thereto, a liquid inlet also thereto, a cover for the chamber with an adjustable spring seat therein, a valve normally seated on the liquid inlet with a stem extended into the cover, a spring within the cover acting normally to seat the liquid inlet valve, and a diaphragm on the stem to 75 be acted upon by the fluid in the mixing chamber to assist in unseating the liquid valve. 70

4. The method of vaporizing liquid which comprises introducing an aeriform under 80 pressure into a mixing and vaporizing chamber, introducing under greater pressure with the aid of the aeriform a liquid into said chamber, vaporizing the liquid therein by the aeriform, and ejecting the same through 85 a spraying head. 85

5. A vaporizer comprising a controller including the body 1, cover 2 therefor, air inlet 24 and liquid inlet 10 to the body, the valve stem 11 seated on said liquid inlet carrying the diaphragm 8 and spring 7 for the stem, the cap 4 for the body and carrying the spring and stem, the outlet member 17 on the body 1, gauge member 18 thereon; and the head 20 connected to the gauge. 90

In testimony whereof, I have signed my name to this specification.

GEORGE W. D'ARCY.
